UNITED STATES PATENT OFFICE

2,536,942

GOLF CLUB CLEANING AND SCRAPING DEVICE

Theodore M. Kanter, Cleveland, Ohio

Application September 10, 1948, Serial No. 48,582

1 Claim. (Cl. 15—111)

1

The present invention comprises a novel cleaning device for cleaning the grooves provided in the faces of the striking heads of golf clubs.

These grooves are provided for the purposes of imparting spin to the golf ball when the grooved face of the club head strikes the same. In the use of golf clubs so provided with grooved club head faces, the said grooves accumulate dirt and mud and pieces of grass or turf from contact of the club head therewith, and such foreign material becomes coagulated in the grooves, thereby reducing or entirely eliminating their effectiveness for the purpose of imparting spin to the ball.

It is quite important to golfers that the grooves in the club head faces be kept free from such accumulated foreign material. It is therefore the object of this invention to provide a handy cleaning device for this purpose which will not only serve to loosen the coagulated foreign material from the grooves, but at the same time remove such foreign material therefrom, all in one operation, so to speak.

The invention will now be described more in detail in conjunction with the accompanying drawings, in which:

Figure 1 is an elevational view of the cleaning device of the invention.

Figure 2 is a bottom plan view of the same.

Figure 3 is a view showing the head of a golf club with the face thereof provided with the grooves to be cleaned by the device of the invention, the latter being shown in dotted lines in position for cleaning.

Figure 4 is a section on the line 4—4 of Figure 3, showing the cleaning device in full lines, partially broken away, disposed for cleaning action.

Figure 5 is a view similar to Figure 2 but illustrating a modification in respect to the scraper blade.

The cleaner device comprises a handle member 1 which may be of spherical shape as shown, for convenient engagement with the hand of the user, and to this handle member 1 is secured one end of a scraper blade member 2. The free end of the blade 2 is sharp or pointed, as illustrated, the sharp or pointed free end being designated by the numeral 2. A plurality of stiff bristles 4 are secured to the handle 1 and extend therefrom in the same direction as the blade 2, the bristles 4 being disposed to surround the blade 2 which is positioned generally at the center of the group of bristles 4.

The blade 2 is tapered or gradually reduced in cross sectional dimension adjacent its free sharp

2

or pointed end 3. In Figure 1 the blade 2 is illustrated as having the conically tapered portion 5 which narrows down to the sharp point 3 at the extreme outer end (see also Figure 2). The portion 5 of the blade 2 has a taper angle preferably corresponding to the angle of taper of the grooves 6 provided in the striking face 7 of the club head generally indicated at 8, such grooved faces being ordinarily provided in respect to those golf clubs usually designated as irons. The grooves 6 are of V-shape in cross section, with the walls of the grooves diverging from the apex at the bottom or base of the grooves upwardly and outwardly to the striking surface 7.

15 Preferably the sharp or pointed end 3 of the blade 2 is flush with the line of the free ends of the bristles 4. The bristles 4 are made of stiff but resilient or yieldable wire-like material, such as steel wire or the like.

20 In the use of my invention the device is employed as a brush to remove coagulated dirt and other foreign material on the face 7 of the golf club head 8. In this connection it will be apparent that the free outer ends of the bristles 4 when

25 pressed into contact with the striking face 7 will have an adequate abrasive or cleaning action, and yet they will be sufficiently resilient or yieldable to permit the tapered portion 5 of the blade 2 to enter the grooves 6 so that the point or sharp

30 end 3 of the blade 2 may be pressed clear down to the bottom narrow apex of the groove 6 to remove foreign material lodged therein. Under such conditions the bristles 4 will yield to permit penetration of the point or sharp end 3 of the blade to the base of the groove 6, and as the tapered portion 5 is moved along the groove with scraping and cleaning action to dislodge the foreign material coagulated therein, the bristles will

35 also enter the groove 6 and serve to brush away 40 the material dislodged by the action of the blade 2.

If desired, another form of blade may be employed, and this is shown in the modification of Figure 5. In this instance the blade 2' is formed of relatively flat metal stock approximately rec-

45 tangular in cross section with the tapered edges 2a and 2b converging to form the sharp edge 2c, the angle of convergence of the tapered edges 2a and 2b approximating the angle of convergence of the walls of the grooves 6 of the striking faces of golf clubs with which the device is to be used 50 for cleaning purposes.

In both constructions of my invention as described the scraper blade member is rigid and unyielding as is necessary for same to perform its 55 function.

Having thus described my invention, what I claim as new and desire to secure by Letters Patent of the United States, is:

A golf club cleaning device of the class described, comprising, in combination, a handle member, an unyielding metal scraping blade rigidly secured thereto at the end thereof opposite its handle portion and having a tapered free end forming a sharp end adapted to enter a tapered groove in the striking face of a golf club head, and a plurality of stiff bristles secured to said handle and disposed around said blade, the bristles extending from the handle substantially parallel to the blade and of approximately the same length as the blade, whereby the sharp end of the latter is substantially flush with the free end of the bristles.
